FUEL FIRED HEATER

Richard E. Teagle, Parma, Ohio, assignor to The Foundry Equipment Company, Cleveland, Ohio, a corporation of Ohio

Filed May 23, 1958, Ser. No. 737,414

6 Claims. (Cl. 263—19)

This invention relates as indicated to a fuel fired heater, and more particularly to a heater desired to deliver a supply of hot air and gases to large foundry molds for the purpose of drying them. It is also suitable for use in many installations where an efficient automatically controlled heater is desired.

Fuel fired heaters and particularly gas fired heaters are frequently employed for the purpose of delivering a considerable volume of heated air and gases to the interiors of large foundry molds to dry the latter prior to casting. For this purpose, large so-called portable heaters have often been utilized which, however, are so heavy and cumbersome that an overhead crane is required to shift them from place to place where needed. Sometimes rather elaborate duct-work has also been required. When relatively small and light heaters of a truly portable nature have been provided comprising principally a burner and a propeller fan, insufficient heat is extracted from the heater for efficient operation. In practice, it is frequently important that the air delivered from the heater be at a predetermined temperature not affected by duct back pressure and the like.

It is accordingly an important object of my invention to provide a novel fuel fired heater adapted to deliver a considerable volume of heated air and gases at a pre-selected temperature regardless of variation in such volume and pressure.

Another object is to provide such heater which will be readily portable and inexpensive but nevertheless highly efficient in operation.

Still another object is to provide such heater utilizing a counterflow air system having the advantage of both utilizing the heated surfaces to the maximum and also substantially eliminating the outer insulation required.

A further object is to provide an integrated burner-fan unit of improved design.

Other objects of the invention will appear as the description proceeds.

To the accomplishment of the foregoing and related ends, said invention then comprises the features herein-after fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a top plan view, partly in section, of a heater embodying the principles of my invention;

Fig. 2 is a transverse section taken on the line 2—2 on Fig. 1; and

Fig. 3 is a side elevation on an enlarged scale.

Referring now more particularly to such drawing, the embodiment of my invention there illustrated comprises a welded metal base or platform 1 on which the several components are mounted. These components comprise principally a burner 2, a blower 3 and a comparatively

2

high pressure fan 4. Burner 2 fits within an inner sheet metal shell 5 entirely enclosed within an outer sheet metal housing 6 providing air passages 7, 8, 9 and 10 therebetween. Such inner shell 5 may desirably project slightly beyond outer housing 6 providing an outlet 11 adapted to be connected to a large mold to be dried or to appropriate duct-work as desired. Cool air is thus admitted around the entire periphery of such outlet 11 and passes inwardly through ducts 7, 8, 9 and 10 to the chamber 12 containing fan housing 13. Air is drawn into such housing through opening 14 generally co-axial with fan 4 and then driven by such fan past burners 2 out of delivery orifice 11. Such air is heated by the burners and also supplies the necessary oxygen for complete combustion of the burner fuel. The inner shell 5 may be very highly heated by the burner and thereby further contribute to heating of the air forced through the shell by fan 4. The incoming air in passages 7, 8, 9 and 10 is, of course, pre-heated to some extent by the hot walls of the inner shell 5 and also serves as an effective insulating medium for the outer housing 6. Heavy and expensive insulating materials are accordingly not required such as are ordinarily found in the usual heater.

Fan 4 is desirably a high pressure fan driven by motor 25 mounted on platform 1.

The burner 2 may be of generally conventional cross-shape design with ports opening toward the delivery orifice 11 of inner shell 5. An appropriate gas-air mixture may be delivered to such burner through duct 16. Such 30 gas-air mixture is delivered to duct 16 by mixer-blower 3 driven by motor 17, air being drawn into such blower through adjustably louvered air inlet shutter 18. Gas such as natural gas may be admitted through gas inlet valve 19 adapted to be connected by means of coupling 35 20 to a gas supply line and thence through a conventional safety shut-off valve 21 to the air inlet 22. The blower 3 thoroughly mixes the gas and air and delivers such mixture to burner 2.

The valve 19 is provided with a differential pressure sensing device 23 which may, for example, be a Reynolds model NRZ regulator which has a diaphragm 24 adapted to move up or down in response to a difference in pressure on the respective sides thereof. A tube 25 leads from the interior of combustion chamber 5 to the upper side of diaphragm 24 while tube 26 leads from conduit 40 16 to the lower side of diaphragm 24.

Operation

Having in mind the foregoing description of the apparatus, the operation of my new fuel fired heater may now readily be understood.

The blower 3 will be driven at constant speed by motor 17 and the shutter 18 will be adjusted to vary the air intake. Thus, it may be assumed that such shutter is set at a half open position for the purpose of the following explanation. When the shutter is thus moved from full open to half open position, there will be a consequent drop in pressure within conduit 16 leading from mixer-blower 3 to burner 2, with proportional drop in pressure at the lower side of diaphragm 24. The consequent shifting of the diaphragm serves partially to close valve 19 and thereby reduce the amount of gas admitted to inlet 22 of mixer-blower 3. As a result, the air and gas mixture will be maintained in the desired proportion for proper combustion at burner 2.

Changes in the back pressure within combustion chamber or inner shell 5 due to changes in the duct system, etc., to which the heated air and gases are delivered do not appreciably affect the delivery of mixer-blower 3 which is a high pressure blower. But even a rather slight change in the back pressure will effect a substantial change in the volume of the main air flow from main air

supply fan 4 which operates at a lower range. Consequently, the total volume of heated air and gases discharged from orifice 11 of combustion chamber 5 (the sum of the main fan discharge and the burner discharge, which latter is a small proportion of the total) will be substantially affected and since the quantity of heat is constant, the temperature of such total discharge will be correspondingly affected. I provide means, however, for automatically compensating for such undesirable effect in the form of tube 25 leading from combustion chamber 5 to the upper side of diaphragm 24. The pressure in such tube is, of course, increased by the aforesaid increase in back pressure and the diaphragm is accordingly shifted further to close the gas inlet valve 19. There will accordingly now be a lower proportion of gas in the gas-air mixture delivered by the mixer-blower 3 to the burner 2 than was the case before, and this is exactly what is desired since due to the back pressure at the burner the main supply fan 4 is no longer effective to deliver as large a volume of air to the burner as before, such air, of course, being required for complete combustion of the gas in the gas-air mixture delivered to the burner.

Furthermore, due to the reduced quantity of gas now available at the burner, less heat is produced and the same final temperature of the heated air and gases of combustion delivered at orifice 11 will be maintained despite the reduced volume of air delivered from blower 4. An important object of my invention is thus accomplished, namely that of automatically maintaining a predetermined temperature of the heater discharge despite variations in the back pressure encountered from time to time. Valve 19 and its regulator perform the function of regulating the gas supply in a manner to compensate both for such variations in back pressure at the heater outlet and also for (manual) adjustment of the air inlet shutter 18. It will be understood that such regulator is not per se a part of my invention, being commercially available, but I have employed it in a novel manner. The entire heater may be of quite lightweight construction and readily portable, considerably enhancing its usefulness in the ordinary foundry. It is, moreover, efficient in the production and conservation of heat and is accordingly relatively inexpensive to operate. Due to its compact arrangement, it is also relatively inexpensive of manufacture.

Other modes of applying the principle of the invention may be employed, change being made as regards the details described, provided the features stated in any of the following claims or the equivalent of such be employed.

I therefore particularly point out and distinctly claim as my invention:

1. In a fuel fired heater having a sheet metal open-ended shell, a gas fired burner therewithin adapted to heat said shell and to release hot gases therewithin, and a high pressure fan positioned at one end of said shell to drive air past said burner through said shell to an outlet therefrom; an outer housing spaced from and enclosing said shell providing air inlet passages to said fan to admit air thereto from inlets disposed peripherally of such outlet from said shell, whereby cool ambient air will flow to said fan in a direction counter to the flow of air and gases within said shell to cool the latter while preheating such air approaching said fan; a mixer-blower having a delivery conduit leading to said burner to deliver a gas-air mixture thereto for combustion, means adapted to regulate admission of ambient air to said blower, a gas inlet valve adapted to admit gas to said blower, a regulator operative to adjust said valve in response to pressure differentials, means connecting said regulator to the interior of said shell, further means connecting said regulator to said delivery conduit of said blower to establish such pressure differentials at said regulator to activate the latter to adjust said valve to move the same toward closed position in response to lower pressure in

said conduit resulting from any reduction in admission of ambient air to said mixer-blower and further to move said valve toward closed position in response to increase in back pressure within said shell tending to reduce air flow therethrough from said fan.

2. A portable fuel fired heater having a base platform, a housing mounted thereon, an inner sheet metal shell within said housing and spaced therefrom, said shell having an open end projecting from said housing, a fan positioned within said housing at the other end of said shell operative to drive air through said shell and out the open end of the latter, air inlet openings to said housing peripherally of such outlet end of said shell for admission of ambient air to said housing and flow of such air between said shell and housing to said fan in a direction opposite to the flow of air through said shell from said fan, a gas fired burner within said shell adapted to heat said shell and to release hot gases therewithin, a constant-speed mixer-blower mounted on said platform having an air inlet thereto and a delivery conduit connected to said burner to deliver a gas-air mixture thereto for combustion, an adjustably louvered air inlet shutter for said air inlet to regulate the admission of ambient air to said mixer-blower, a gas inlet valve adapted to admit gas to said air inlet of said mixer-blower, a regulator operative to adjust said valve in response to pressure differentials, means connecting said regulator to the interior of said shell, further means connecting said regulator to said delivery conduit of said mixer-blower to activate said regulator to adjust said valve to move the latter toward closed position in response to lower pressure in said conduit resulting from reduction in admission of ambient air to said mixer-blower by partial closing of said shutter and further to move said valve toward closed position to reduce admission of gas to said mixer-blower in response to increase in back pressure within said shell tending to reduce air flow through the latter from said fan.

3. The heater of claim 2, wherein said regulator is of the diaphragm type, with said connection to said shell leading to one side of said diaphragm and the connection to said conduit leading to the other side of said conduit.

4. A portable, compact fuel-fired heating apparatus adapted for easy transportation to and from various stations of use, said apparatus including a substantially rectangular platform, a sheet metal shell supported along one side of the platform in the general direction of the greater length of said platform, a gas-fired burner carried within said shell adapted to heat the same and release hot gases therein, a high pressure fan supported on the platform in substantially axial alignment with said shell and adapted to force air into said shell past said burner and out the opposite end of the shell which thereby defines an outlet, an outer housing spaced from and enclosing said shell to provide air inlet passages to said fan and admit air thereto from inlets disposed peripherally of such outlet from said shell, whereby cool ambient air will flow to said fan in a direction counter to the flow of air and gases within said shell to cool the latter while preheating such air approaching said fan, a mixer-blower carried by said platform laterally of said shell and at a point substantially corresponding to the position of the burner within the shell, a conduit connecting said mixer-blower and said burner to transmit a gas-air mixture, means adapted to regulate the admission of ambient air to said mixer-blower, a gas inlet valve adapted to admit gas to said blower, regulating means including a diaphragm valve to adjust such gas inlet valve, said regulating means being supported laterally of said shell and above the mixer-blower means, means connecting said regulating means to the interior of said shell to move said gas inlet valve toward a closed position in response to back pressure within said shell tending to reduce air flow therethrough from said fan, and further means connecting said regulating means to said conduit to move said gas inlet valve toward a closed position in response to lower

pressure in said conduit resulting from any reduction in admission of ambient air to said mixer-blower.

5. A portable, compact gas-fired heating apparatus adapted to discharge heated gases of substantially constant temperature although of varying volume, said apparatus including a substantially rectangular base platform permitting the entire apparatus to be easily transported to and from various stations of use, a sheet metal shell supported along one side of said base platform in the general direction of the greater length of said platform, a gas-fired burner carried within said shell adapted to heat the same and release hot gases therewithin, a high pressure fan supported on the platform in substantial axial alignment with said shell and adapted to force air into said shell past said burner and out the opposite end of the shell which thereby defines an outlet, an outer housing spaced from and enclosing said shell to provide air inlet passages to said fan and to admit air thereto from inlets disposed peripherally of such outlet from said shell, whereby cool ambient air will flow to said fan in a direction counter to the flow of air and gases within said shell to cool the latter while preheating such air approaching said fan, a constant-speed mixer-blower carried by said base platform laterally of said shell and at a point substantially corresponding to the position of the burner within the shell, a delivery conduit connecting said mixer-blower and said burner to transmit a gas-air mixture to the latter, said mixer-blower having an air inlet thereto, an adjustably louvered air inlet shutter for said air inlet to regulate the admission of ambient air to said mixer-blower, a gas inlet valve adapted to admit gas to said

mixer-blower, regulating means including a diaphragm valve to adjust said gas inlet valve, said regulating means being supported laterally of said shell and above the mixer-blower, pressure connecting means joining the interior of said shell to one side of the diaphragm of the diaphragm valve to move said gas inlet valve toward a closed position to reduce admission of gas to said mixer-blower in response to an increase in back pressure within said shell tending to reduce air flow through the latter from said fan, and further pressure connecting means joining said delivery conduit to the other side of the diaphragm of said diaphragm valve to move said gas inlet valve toward a closed position in response to lower pressure in said conduit resulting from reduction in the admission of ambient air to said mixer-blower by partial closing of said shutter, thereby to maintain a predetermined temperature on the discharge of said outlet of the shell release of variations in the volume discharged because of back pressure and the like.

20 6. The heating apparatus of claim 5 including a motor to drive said fan, a constant-speed motor to drive said mixer-blower, and a safety shut-off valve supported adjacent and in serial connection with said gas inlet valve.
